A. E. PUERNER,
CIRCUIT CLOSER FOR CONTROLLING ELECTRIC LIGHTS,
APPLICATION FILED SEPT. 27, 1919.

1,411,300.

Patented Apr. 4, 1922.

UNITED STATES PATENT OFFICE.

ALBERT E. PUERNER, OF FORT ATKINSON, WISCONSIN.

CIRCUIT CLOSER FOR CONTROLLING ELECTRIC LIGHTS.

1,411,300.

Specification of Letters Patent.

Patented Apr. 4, 1922.

Application filed September 27, 1919. Serial No. 326,955.

To all whom it may concern:

Be it known that I, ALBERT E. PUERNER, a citizen of the United States, residing at Fort Atkinson, in the county of Jefferson and State of Wisconsin, have invented certain new and useful Improvements in Circuit Closers for Controlling Electric Lights, of which the following is a specification, reference being had to the accompanying drawings.

This invention relates to means for controlling electric lights and has relation more particularly to means for controlling the electric lamps of automobile headlights, and it is an object of the invention to provide novel and improved means whereby the lamps are arranged in multiple or in series in accordance with the speed of the engine, so that the possibility of the lamps burning out when the engine is running on low gear is substantially eliminated.

The invention consists in the details of construction and in the combination and arrangement of the several parts of my improved means for controlling electric lights whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a diagrammatic view with parts in elevation and parts in section, of means for controlling electric lights arranged in accordance with an embodiment of my invention, and,

Figure 2 is a fragmentary view partly in elevation and partly in cross section of certain of the parts illustrated in Figure 1.

As disclosed in the accompanying drawings L denotes the lamps connected in series in a well known manner by the conductors a, one of said conductors being grounded and a second conductor being electrically connected with the post 1 comprised in the regulating device embodied in the present invention.

The regulating device comprises a casing or housing C provided with a bracket B whereby said casing or housing C may be supported by the dash of an automobile body

at a point in close proximity to the steering gear and preferably slightly therebelow. The lower wall 2 of the casing or housing C is provided with a pair of longitudinally spaced slots 3 through which extend the lugs 4. Slidably disposed through the lugs 4 is an end portion of a rod 5 and the opposite end portion of said rod 5 is operatively engaged with a bracket 6, operatively engaged with the clutch shaft of the transmission when the device is employed in connection with the well known Ford type of car.

The lugs 4 depend from the opposite end portions of a slide 7 arranged within the casing or housing C and slidably mounted upon the lower wall 2. Supported by the central portion of the slide 7, but insulated therefrom, is a bracket 8 of conductive material, and having a portion 8^a overlying the slide 7. The portion 8^a is provided with a slot 9 through which extends a spring conductor 11 arranged within the casing or housing C, and in electrical connection with the post 12.

The post 12 is disposed through the upper wall 14 of the casing or housing C, and insulated therefrom, and arranged at one side of the post 1, hereinbefore referred to. The post 12 has engaged therewith a conductor b leading from a magneto driven in a well-known manner by the engine of the automobile. Interposed in the conductor b is a switch 15 of a conventional type.

Also mounted upon the slide 7, which is of metal or other conductive material, and in electrical connection therewith is a second bracket 16, having an upper portion substantially aligned with the portion 8^a of the bracket 8, but spaced therefrom. Extending between said brackets 8 and 16 is an end portion of a resilient conductor plate 17 depending from the top wall 14 of the casing or housing C, and in electrical connection with the post 1 carried by said wall 14, but insulated therefrom.

Also disposed through the wall 14 and insulated therefrom is a post 18. Leading from the post 18 is a conductor c in electrical connection with a conductor a at a point between the lamps L. When the slide 7 is moved in one direction when the transmission is in high gear, the bracket 8 is brought into electrical contact with the resilient or spring conductor 19 depending from the post 18, and whereby the lamps L are caused to burn in multiple as a circuit

for one of the lamps is grounded through the second bracket 16, which is also in electrical contact with the resilient conductor plate 17. This ground is obtained through 5 the lugs 4, which are of conductive material and in electrical connection with the slide 7 and the rod 5. When the transmission is thrown into low, the movement of the slide 10 7 results in the lamps L burning in series as the bracket 8 is only in electrical contact with the conductor plate 17.

Affixed to the rod 5 between the lugs 4, is a collar 20, which normally contacts with one of the lugs 4 and whereby the rod 5 is 15 caused to impart desired movement to the slide 7 when the clutch shaft is rocked into low. Interposed between the collar 20 and the second lug 4 is an expansible member 21, herein disclosed as a coil spring encircling 20 the rod 5, and which operates to permit the rod 5 to impart the desired movement to the slide 7 when the clutch shaft is moved into high, and at the same time permits an independent movement of the rod so that no 25 obstruction or hindrance is offered to the requisite operation of the clutch shaft.

From the foregoing description, it is thought to be obvious that a means for controlling electric lights, constructed in accordance 30 with my invention is particularly

well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:

A circuit closer comprising a supporting member, a pair of contact plates carried by 45 said supporting member, a sliding contact coacting with one of the contact plates, a bracket carried by and insulated from the sliding contact and positioned between the contact plates, said bracket engaging one 50 of the plates when free of the other, said sliding contact being engaged with one of the plates when the bracket is free thereof and in contact with the second plate, and a conductor in constant electrical connection 55 with the bracket.

In testimony whereof I hereunto affix my signature.

ALBERT E. PUERNER.
